UNITED STATES PATENT OFFICE.

AUGUST J. REBSTOCK, OF ST. LOUIS, MISSOURI, ASSIGNOR TO ALVEY MANUFACTURING COMPANY, OF ST. LOUIS, MISSOURI, A CORPORATION OF MISSOURI.

CONVEYER.

Application filed July 11, 1921. Serial No. 483,752.

To all whom it may concern:

Be it known that I, AUGUST J. REBSTOCK, a citizen of the United States, and a resident of the city of St. Louis and State of 5 Missouri, have invented a new and useful Improvement in Conveyers, of which the following is a specification.

This invention relates to conveyers of the type wherein packages are delivered by 10 means of a gravity conveyer upon the lower end of an elevating-conveyer or inclined elevator having pushing or propelling elements adapted to engage the rear ends of said packages and force the same upwards along the 15 bed of said elevator to the discharge end thereof.

One of the principal objections to the above type of elevator is that the packages 20 are often fed to the receiving end of the elevator in such position as to be engaged on their under sides by a rising pushing element, instead of being engaged at their rear ends as is required for the proper propulsion of the packages along the bed of the elevator. This engagement of the under sides of 25 the packages by the propelling elements, if occurring too far back from the front end of the packages to permit said elements to pass from under said packages, causes the packages to be dragged partway up the inclined bed of the elevator; and said packages when drawn upwardly in this manner often slide backwards and strike the package 30 following, thus damaging both packages and the contents thereof and sometimes even causing one or the other or both to leave the elevator and fall to the floor.

The principal object of the present invention 35 is to provide a simple, inexpensive and efficient arrangement for protecting the packages against this action. Another object is to enable the power driven chain, which carries the propelling elements, to be adjusted without changing the distance between 40 the stop device and the plane of the rising propelling elements. Another object is to provide an adjustable mount for the endmost conveyer roller at the delivery end of 45 the gravity conveyer, whereby a uniform space may be maintained between said roller and the plane of the rising propelling elements.

The invention consists principally in the 50 improved stop device for holding the packages in position to be properly en-

gaged by the propelling devices; it also consists in operatively connecting said stop device with the sprocket wheels of the elevator so as to be adjustable therewith; it also consists in the means for adjusting the 60 endmost roller of the gravity conveyer towards and away from said sprocket wheels; and it also consists in the combinations and arrangements of parts hereinafter described and claimed.

In the accompanying drawings, which 65 form part of this specification, and wherein like symbols refer to like parts wherever they occur,

Fig. 1 is a plan view of the adjacent end 70 portions of a gravity conveyer and an inclined elevator provided with improvements embodying my invention;

Fig. 2 is a vertical longitudinal section 75 on the line 2—2 in Fig. 1;

Fig. 3 is a vertical cross-section through 80 the elevator on the line 3—3 in Fig. 2; and

Figs. 4 and 5 are a side elevation and a 85 plan view, respectively, of the delivery end of the gravity conveyer, the endmost roller being shown extended in dotted lines.

The conveying device shown in the accompanying drawings comprises a gravity conveyer A and an inclined power driven elevator B, whose receiving end is arranged 90 adjacent to the delivery end of said gravity conveyer and is suitably connected therewith.

The gravity conveyer A comprises spaced 95 side rails 5 of the angle section having a bed of rollers 6 disposed crosswise thereof whose ends are rotatably supported in said side rails. The endmost roller 7 of the feeding conveyer A is located beyond the 100 ends of the side rails 5 and has its ends journaled in brackets 8, which are riveted to the upper surfaces of supporting plates 9 at one end thereof. These plates extend beneath the outwardly projecting horizontal flanges 105 of the side rails 5 and are secured to the under sides thereof by means of bolts 10, which project through elongated slots 11 in the plates and holes in the said flanges and are provided on the upper ends with nuts. The slots extend longitudinally of the 110 conveyer rails 5, whereby the supporting plates are adapted to be shifted longitudinally of the gravity conveyer to adjust the endmost roller 7 with respect to the receiving end of the elevator.

The inclined elevator or power conveyer B comprises a bed or way in the form of a plate 12 having a horizontal receiving portion and an inclined portion adapted to extend to an upper floor or level (not shown). The way is suitably supported by a frame comprising standards 13. Running between upper and lower pairs of angles 14 and 15, which form part of the elevator-frame and extend longitudinally thereof on opposite sides of the bed, are the upper and lower stretches of a pair of endless conveyer chains 16. The pairs of angles 14 and 15 serve as guides for the upper and lower stretches of the endless chains 16 which run therebetween, the lowermost angles of each pair constituting supports for said chains. The sprocket chains 16 pass around idler sprocket wheels 17, which are fixed to the opposite ends of a transverse shaft 18 located beneath the way adjacent to the receiving end thereof. The shaft 18 has its ends journaled in bearing blocks 19, which are slidably supported between vertically spaced horizontally disposed angles 20 secured to the vertical members of the frame.

The slide-blocks 19 may be adjusted longitudinally of the frame, to tighten or loosen the sprocket chains 16, by means of horizontally disposed screws 21, which are connected to said slide-blocks. The screws 21 work in nuts 22 located on opposite sides of a vertically disposed angle member of the elevator frame and are provided with hand wheels 23 to facilitate turning thereof. At the upper end of the elevator the chains 16 pass over power driven sprocket wheels (not shown).

The chains 16 carry package engaging devices in the form of spaced pusher bars 24, which are disposed crosswise of the way and having their ends connected to said chains. These pusher bars move with the chains, and pass above and below the way and upwardly around the receiving end thereof, the spacing of the bars depending upon the size of the article to be conveyed.

The lower end of the way terminates short of the sprocket wheels 17 and is provided with an extension in the form of a plate 25. This plate rests upon the horizontal portion of the way and is slidably connected therewith by means of strips 26. The strips 26 are secured to the longitudinal marginal portion of the slide plate 25 and project beneath the slide marginal portions of the way, whereby said extension is permitted to slide longitudinally of the bed and is held from upward movement with respect thereto.

Fixed to the sprocket shaft 18 are corrugated feed rolls 27. These rolls are disposed with their outer ends substantially flush with the side edges of the bed-extension 25 and are spaced apart on opposite

sides of the longitudinal center line of the bed. The bed-extension 25 has a reduced centrally disposed portion 28 which extends between the spaced feed rolls 27, said portion 28 being supported by and secured to the sprocket shaft 18 by means of angles 29. These angles 29 have one flange riveted to the under side of the reduced portion 28 of the bed-extension and their other flanges are provided with alined holes through which the sprocket shaft extends. The extension 25 is disposed with its upper surface below the upper surfaces of the feed rolls 27 and above the plane of the bed of the feeding conveyer A; and the outer marginal portion, the reduced end portion 28 of said extension terminates in the form of a depending stop-flange 30. The flanged edge 30 of the narrow portion of the bed-extension terminates short of the plane of the pusher bars 24 on the upwardly moving portion of the chains 16 to enable said bars to clear the same; and the endmost roller 7 of the gravity conveyer A is adapted to be adjusted in the manner hereinbefore described to enable said roller to clear the upwardly moving pusher bars.

With the arrangement described, packages travel along the gravity conveyer A and upon reaching the discharge end thereof are engaged by the stop-flange 30 which prevents further travel thereof. The stop 30 engages the lower edges of the front walls of a package and holds said package stationary with its front end portion overhanging the path of the rising pusher bars. The under side of the package is then engaged by one of the upwardly moving pusher bars which lifts the front corner of the package over the stop upon the rotating feed rollers. This pusher bar then moves out from under the package which is then fed forward on the extension of the horizontal portion of the elevator bed, by the rotating feed rollers. During the lifting of the package over the top and the feeding of said package upon the extension of the bed, another package will have been engaged by the stop and the succeeding pusher bar will lift this package clear of said stop and upon the feed rollers and will pass from under said package and will engage the rear end of the first mentioned package and propel the same along the inclined portion of the way to the discharge end of the elevator. This arrangement renders certain the engagement of the rear ends of the packages by the pusher bars, during the movement of said pusher along the inclined portion of the bed, and will also permit handling of the packages of different sizes and shapes. This arrangement also eliminates the necessity for timing the arrival of the packages at the receiving end of the elevator; it also eliminates the neces-

sity for placing the packages on the gravity conveyer in spaced relation or at regular intervals; and it also eliminates the use of spring devices for retarding the movement 5 of packages upon the bed of the elevator, which devices are not adapted for use in connection with packages of different sizes and shapes.

The extension 25 of the bed 12 has a sliding connection therewith and is secured to the sprocket shaft 18, which arrangement permits said extension to move with said shaft when the same is adjusted to take up slack in the sprocket chains. Thus a uniform space is maintained between the stop flange 30 and the rising pusher bars, regardless of adjustment of said shaft. Uniform space between the endmost roller 7 of the gravity conveyer and the rising pusher 15 bars may also be maintained by adjusting said roller towards or away from the said pusher bars.

It is noted that the use of the stop device will not interfere with the use of the 20 elevator for lowering packages instead of elevating them.

The invention is not restricted to the precise forms and arrangements shown in the drawings.

33 What I claim is:

1. In a conveyer comprising a package way and spaced traveling devices for propelling packages along the same, a feeding device operatively connected with said traveling devices and projecting above said way, said devices passing above and below said way and upwardly around the receiving end of said way and said feeding device, the receiving end of said way having a stop 35 rigid therewith and located inside of the path of the traveling devices, and means for feeding a package against said stop, whereby said package will be engaged by an upwardly moving traveling device and lifted 40 clear of said stop and deposited upon said feeding device which feeds said package upon said bed in a position to be engaged at its rear end by a succeeding traveling device.

50 2. In a conveyer comprising a package way and spaced traveling devices for propelling packages along the same, a rotating feeding device projecting above said way, said traveling devices passing continuously 55 above and below said way and upwardly around the receiving end of said way and said feeding device, means for feeding a package to the receiving end of said conveyer, and fixed means located at the receiving end of said way for stopping said package with its front end portion overhanging the path of the upwardly moving traveling devices, whereby the front end portion of 60 said package will be engaged on its underside by an upwardly moving traveling de-

vice and lifted over said fixed stop upon said feeding device which moves said package upon said bed in a position to be engaged at its rear end by a succeeding traveling device.

3. In a conveyer comprising a package way and spaced traveling devices for propelling packages along said way, a rotary feeding device operatively projecting above said way, said traveling devices passing continuously above and below said bed and upwardly around the end of said way and said feeding device, means for feeding a package to the receiving end of said bed in a plane disposed below the plane of said bed, whereby said end constitutes a stop that holds said package with its front end portion in the path of the upwardly moving traveling devices and said portion of said package will be engaged on its under side by a rising traveling device and lifted over said end of said way upon said feeding device which moves said package upon said bed in a position to be engaged at its rear end by a succeeding traveling device.

4. In a conveyer having a package way comprising a horizontal receiving portion and a portion inclined upwardly therefrom, traveling devices for propelling packages along said way, a feeding device located adjacent to the end of said way, said feeding device being operatively connected with said traveling devices and projecting above the plane of the horizontal portion of said way, said traveling devices passing continuously above and below said way and said feeding device and upwardly around the end of the receiving portion of said way and said feeding device, means for feeding a package to the end of the receiving portion of said way in a plane located below the plane of said receiving portion, whereby said end of said receiving portion constitutes a stop adapted to hold said package with its forward end portion in the plane of the traveling devices and said portion of said box will be engaged on its under side by a rising traveling device and lifted over said end of said way onto said feeding device which moves said package upon said bed in a position to be engaged at its rear end by a succeeding traveling device.

5. In a conveyer comprising a package way, a transverse shaft disposed below said way adjacent to the receiving end thereof, sprocket wheels fixed to said shaft on opposite sides of said way, feed rolls fixed to said shaft between said sprocket wheels and extending above said way, chains passing over said sprocket wheels, propelling devices carried by said chains, said devices being adapted to pass above and below said way and upwardly around the receiving end of said way and said feed rolls, and means for feeding the packages to the receiving end of

said way in a plane located below the plane thereof, whereby the end of said receiving portion constitutes a stop for holding said package, with its front end portion in the 5 plane of the rising propelling devices and said front end portion of said package will be engaged on its under side by a rising propelling element and lifted over the said end of said way upon said feed rolls which 10 move said package upon said way in a position to be engaged at its rear end by a succeeding propelling device.

6. In a conveyer comprising a package way, a transverse shaft disposed below said way adjacent to the receiving end thereof, sprocket wheels fixed to said shaft on opposite sides of said bed, feed rolls fixed to said shaft between said sprocket wheels and extending above said way, chains passing over said sprocket wheels, propelling devices carried by said chains, said devices being adapted to pass above and below said way and upwardly around the receiving end of said way and said feed rolls, the receiving 25 end of said way having a stop located inside of the plane of the upwardly moving propelling devices, and means for feeding a package against said stop, whereby the front end portion of said package will be engaged 30 on its under side by an upwardly moving propelling device and lifted clear of said stop and positioned upon said feed rolls which feed said package upon said bed in a position to be engaged at its rear end by 35 a succeeding propelling device.

40 7. In a conveyer comprising a package way, a transverse shaft located below said way adjacent to the receiving end thereof, sprocket wheels fixed to said shaft on opposite sides of said way, chains passing over said sprocket wheels, package propelling devices disposed crosswise of said way and connected to the chains on opposite sides thereof, whereby said devices are adapted to pass above and below said way and upwardly around the receiving end thereof, the receiving end of said way being of reduced width, feed rolls fixed to said shaft on opposite sides of said reduced portion, said reduced portion having a portion disposed beyond the peripheral surfaces of said feed rolls and constituting a stop, and means for feeding a package against said stop, whereby the front end portion of said packages will be engaged by an upwardly moving propelling device and lifted clear of said stop portion and deposited upon said feed rolls which feed said package upon said bed in a position to be engaged at its rear end by a succeeding propelling device.

8. In a conveyer comprising a package way, a transverse shaft located below said way adjacent to the receiving end thereof, sprocket wheels fixed to said shaft on opposite sides of said way, chains passing over

9. In a conveyer comprising a package way, a transverse shaft located below said way adjacent to the receiving end thereof, sprocket wheels fixed to said shaft on opposite sides of said way, chains passing over said sprocket wheels, package propelling devices disposed crosswise of said way and connected to the chains on opposite sides thereof, whereby said devices are adapted to pass above and below said way and upwardly around the receiving end of said way, the receiving end of said way having a centrally disposed portion of reduced width, feed rolls fixed to said shaft on opposite sides of said reduced portion, said reduced portion having a portion disposed beyond the peripheral surfaces of said feed rolls and constituting a stop, and means for feeding a package against said stop, whereby the front end portion of said packages will be engaged by an upwardly moving propelling device and lifted clear of said stop portion and deposited upon said feed rolls which feed said package upon said bed in a position to be engaged at its rear end by a succeeding propelling device, said feeding means comprising a gravity conveyer having spaced rollers, the endmost roller being adjustable towards and away from the plane of the upwardly moving propelling devices. 115

10. In a conveyer comprising a package way, a transverse shaft located below said way adjacent to the receiving end thereof, sprocket wheels fixed to said shaft on opposite sides of said way, chains passing over said sprockets, package propelling devices carried by said chain and extending cross-wise of said way and adapted to pass above and below the same and upwardly around the receiving end thereof, the receiving end of said way being of reduced width, feed rolls fixed to said shaft on opposite sides of

- said reduced portion, said reduced portion terminating at a point beyond the peripheral surface of said feed rolls, and means for feeding a package to said reduced portion 5 in a plane disposed below the plane thereof, whereby the end of said reduced portion constitutes a stop for said package and holds said package with its forward end portion in position to be engaged on its under side 10 by an upwardly moving propelling device and lifted clear of the end of said reduced portion and deposited upon said feed rolls which feed said packages upon said way in a position to be engaged by a succeeding 15 propelling device, said feeding means comprising a gravity conveyer having spaced rollers, the endmost roller being adjustable towards and away from the plane of the upwardly moving propelling devices.
- 20 11. In a conveyer comprising a package way having a separate extension at one end thereof, a transverse shaft located below said extension, sprocket wheels fixed to said shaft on opposite sides of said extension, chains passing over said sprockets, package propelling devices extending transversely of said way and connecting the chains with each other, said propelling devices being adapted to pass above and below said way and upwardly around the outer end of said extension, and means for adjusting said shaft longitudinally of said way, said extension being connected with said shaft whereby a uniform clearance is maintained between the end of said extension and the plane of the upwardly moving propelling devices regardless of adjustment of said shaft.
- 25 12. In a conveyer comprising a package way having a separate extension at one end thereof, a transverse shaft located below said extension, sprocket wheels fixed to said shaft on opposite sides of said extension, chains passing over said sprockets, package propelling devices extending transversely of said way and connecting the chains with each other, said propelling devices being adapted to pass above and below said way and upwardly around the outer end of said extension, and means for adjusting said shaft longitudinally of said way, said extension being connected at its outer end with said shaft and having a slidible connection with said way at its inner end, whereby said extension is adapted to move with said shaft during the adjustment of the same thereby maintaining a uniform clearance between the end of said extension and the plane of the upwardly moving propelling devices.
- 30 13. In a conveyer comprising a package way having a separate extension at one end thereof, a transverse shaft located below said extension, sprocket wheels fixed to said shaft on opposite sides of said extension, chains passing over said sprockets, package propelling devices extending transversely of said way and connecting the chains with each other, said propelling devices being adapted to pass above and below said way and upwardly around the outer end of said extension, means for adjusting said shaft longitudinally of said way, said extension being connected to said shaft, whereby a uniform clearance is maintained between the end of said extension and the plane of the upwardly moving propelling devices regardless of adjustment of said shaft, and a gravity conveyer leading to the end of said extension, said gravity conveyer comprising rotatably supported rollers the endmost one of which is adjustable towards and away from the plane of the upwardly moving propelling devices, whereby a uniform clearance may be maintained between said roller and said plane of said rising propelling devices.
- 35 14. In a conveyer comprising a way, a transverse shaft located beyond the receiving end of said way, means for adjusting said shaft longitudinally of said way, an extension lapping said end of said way and having a portion of reduced width projecting across said shaft and connected thereto, feed rollers fixed to said shaft on opposite sides of said reduced portion, sprocket wheels fixed to said shaft on opposite sides of said way, chains passing over said sprockets, propelling devices extending transversely of said way and connecting the chains with each other, said propelling devices being adapted to pass above and below said way and upwardly around the outer edge of said extension and said feed rolls, and means for feeding a package to said extension in a plane disposed below the plane thereof, whereby the end of the reduced portion of said extension constitutes a stop for holding the front end portion of said package in the plane of the propelling devices on the upwardly moving portions of said chains.
- 40 15. In a conveyer comprising a way, a transverse shaft located beyond the receiving end of said way, means for adjusting said shaft longitudinally of said way, an extension lapping said end of said way and having a portion of reduced width projecting across said shaft and connected thereto, feed rollers fixed to said shaft on opposite sides of said reduced portion, sprocket wheels fixed to said shaft on opposite sides of said way, chains passing over said sprockets, propelling devices extending transversely of said way and connecting the chains with each other, said propelling devices being adapted to pass above and below said way and upwardly around the outer edge of said extension and said feed rolls, and means for feeding a package to said extension in a plane disposed below the plane

6
thereof, whereby the end of the reduced portion of said extension constitutes a stop for holding the front end portion of said package in the plane of the propelling devices 5 on the upwardly moving portions of said chains, said feeding means comprising a gravity conveyer having a bed of rotatably

supported rollers, the endmost roller being adjustable towards and away from the plane of the propelling devices on the upwardly moving portions of said chains. 10

Signed at St. Louis, Missouri, this 8th day of July, 1921.

AUGUST J. REBSTOCK.
